GAS BURNER WITH CRIMPED RIBBON PORT STRUCTURE

Frank E. Hanson, Evansville, Ind., assignor to
Servel, Inc., New York, N. Y., a corporation of
Delaware

Application February 11, 1947, Serial No. 727,925

6 Claims. (Cl. 158—116)

1

My invention relates to gas burners and more particularly to an improvement in ribbon type burners.

The object of my invention is to provide a burner formed by a plurality of crimped ribbons arranged in side by side relationship to provide interstices therebetween and in which the use of parts in addition to the crimped ribbons to prevent the meshing and buckling of ribbons is avoided.

I achieve the above and other objects and advantages of my invention by forming the adjacent crimped ribbons with a different number of crimps per unit of length as explained in the following description of my invention when taken in conjunction with the accompanying drawings in which:

Fig. 1 is a top plan view of a burner head incorporating my invention;

Fig. 2 is a side elevational view, partly in section, of the burner illustrated in Fig. 1;

Fig. 3 is a part sectional view taken generally on line 3—3 of Fig. 1; and

Fig. 4 is an enlarged plan view of a portion of the burner shown in Fig. 1.

In the embodiment of the invention illustrated in the drawings, the gas burner comprises a generally H-shaped burner head 10 provided with a depending collar 11, see Fig. 2, which snugly fits over an upstanding tapered neck 12 formed on a conventional mixing tube 13, whereby the burner head is removably supported on the mixing tube. Burner head 10, preferably formed as a hollow casting, has two longitudinal branches 14 connected by an integral bridge 15. The bridge 15 is formed by two side walls 15a and a top wall 15b which form a transverse passage 16. Each of the branches 14 provide a longitudinal passage 17 which communicates midway its length with the transverse passage 16. Transverse passage 16 is in open communication with the upstanding neck 12 of the mixing tube 13, the arrangement being such that a combustible air-gas mixture passes upwardly through mixing tube 13 into the transverse passage 16 and from there into longitudinal passages 17. The top face of each of the branches 14 is flat with a longitudinal slot 18 therein in open communication with the longitudinal passage 17. The slots 18 are preferably formed by a machining operation to cut the top and end walls of the branches 14.

In order to properly distribute the air-gas mixture throughout the length and breath of the slots 18 and to prevent the flame of the burning air-gas mixture at the top of the burner

head 10 from flashing back through the mixing tube 13, a plurality of crimped strips or ribbons 19 are provided in each of the slots 18. The number of ribbons 19 placed in the longitudinal slots 18 will vary in accordance with the width of the slot and the ribbons are supported at their ends by the transverse end walls 20 of branches 14 and at their middle by a bridge member 21. The ribbons 19 may be welded or otherwise secured at their end and mid-portions, or they may be arranged to float lengthwise in the slots. However, because of their hereinafter described construction, all of the ribbons 19 are free to expand and contract without extension or buckling and it is therefore preferable to secure the ribbons in the slots 18.

Each of the ribbons 19 consists of a thin strip of a suitable heat resistant material and of appreciable height, corresponding to the depth of the slots 18. The ribbons 19 are crimped or corrugated throughout their length to provide alternate crests 22 and 23 which project from opposite sides of the ribbons.

In accordance with my invention, and as most clearly shown in Fig. 4, the adjacent ribbons 19 in each slot 18 have a different number of corrugations per unit of length. As illustrated in the drawing only two sets of ribbons 19 are provided but a greater number of sets may be used. One of the sets of ribbons 19 is indicated by numeral 19a and the other set of ribbons is indicated by numeral 19b. The ribbons in set 19a are coarsely crimped having a lesser number of crests per unit of length than the ribbons in set 19b which are finely crimped. The crests in ribbons 19a are therefore larger than the crests in ribbons 19b. While the number of crimps per unit of length in the two sets of ribbons 19a and 19b may have infinite variations, a burner for use with natural gas comprising alternate ribbons having 8 and 11 crimps per inch, respectively, and a burner for use with manufactured gas comprising alternate ribbons having 11 and 16 crimps per inch, respectively, have been found to have good operating characteristics.

In assembling the ribbons 19 in the slot 18 the ribbons 19a and 19b are arranged alternately in side by side relationship in the slot, the ribbons 19a being separated from each other by a ribbon 19b and vice versa. In this manner each ribbon 19 has a ribbon immediately adjacent to it which possesses a greater or lesser number of crests of a different size per unit of length. At irregularly spaced points a crest 22 of a ribbon 19a will abut against a crest 23 of

a ribbon 19b. In this manner the adjacent ribbons are held in spaced relationship. The spaces 24 between the adjacent ribbons serve as gas ports for the burner. As the surfaces of the adjacent ribbons 19 differ in shape, the ribbons cannot mesh and therefore no parts, such as flat spacer strips heretofore used, are needed to prevent the meshing of the ribbons. As all the ribbons 19 in the burner are crimped, they can easily expand and contract upon heating and cooling without any extension in their overall length, and thus no constructional parts are needed to prevent buckling of the ribbons.

Various changes may be made within the scope of the invention. For example, the casing of the burner head may take other forms such as a cylinder and the opening for the ribbons may be circular or have any other suitable shape. Therefore without limiting myself in this respect, the invention is defined by the following claims.

What is claimed is:

1. A ribbon burner comprising a burner head having an opening therein, a plurality of crimped ribbons arranged in side by side relationship in the opening, each of said ribbons being crimped uniformly throughout its length, and the contiguous portions of adjacent ribbons having a different number of crimps per unit of length so selected that crests on adjacent ribbons abut at spaced intervals to hold the ribbons in spaced relationship.

2. A ribbon burner comprising a burner head having an opening therein, a plurality of crimped ribbons arranged in side by side relationship in the opening, each of said ribbons being of continuously undulating form to provide uniform crimps throughout its length, and the adjacent ribbons having an odd and even number of crimps per unit of length, respectively.

3. A ribbon burner comprising a burner head having an opening therein, a plurality of crimped ribbons in the opening in the burner head, and the adjacent ribbons being of sinuous form throughout their length to provide alternate crests projecting from opposite sides and having a different number of crests per unit of length to contact each other at a plurality of spaced points throughout the area of the opening and thereby hold the ribbons in spaced relationship.

4. A ribbon burner comprising a burner head having an opening therein, a plurality of crimped ribbons arranged in side by side relationship in the opening in the burner head, each of said ribbons being continuously corrugated throughout its length to provide uniformly spaced crests projecting from opposite sides thereof and the contiguous portion of adjacent ribbons having a different number of corrugations per unit of length so that certain of the crests of adjacent ribbons contact each other at spaced points throughout the area of the opening.

5. A ribbon burner comprising a generally H-shaped burner head having spaced parallel branches connected by a transverse bridge, said parallel branches of the burner head having longitudinal slots therein, crimped ribbons arranged in side by side relationship in the slots in the burner head, each of said ribbons being continuously corrugated to provide uniformly spaced crests, and the adjacent ribbons in each of the slots having a different number of crests per unit of length.

6. A ribbon burner comprising a burner head having an opening in the top thereof, a plurality of sets of continuously undulating crimped ribbons to provide crests projecting from opposite sides of each ribbon, the ribbons of one set having a different number of crests per unit of length than the ribbons of the other set without a common divisor, and said ribbons being arranged in side by side relationship in the opening in the burner head with the ribbons of one set alternating with the ribbons of the other set so that crests of adjacent ribbons abut each other at spaced points to hold the ribbons spaced from each other.
